FIG.9

FIG.10

FIG. 1 is a left end, top and front perspective view of a portable phonograph or similar article, showing my new design in closed condition;

FIG. 2 is a top plan view of the phonograph, in closed condition;

FIG. 3 is a front elevational view of the phonograph, in closed condition;

FIG. 4 is a rear elevational view of the phonograph, in closed condition;

FIG. 5 is a left end elevational view of the phonograph, in closed condition;

FIG. 6 is a right end elevational view of the phonograph, in closed condition;

FIG. 7 is a left end, top and front perspective view of the phonograph, in opened condition;

FIG. 8 is a left side elevational view of the phonograph, in opened condition, the right side being substantially a mirror image thereof;

FIG. 9 is a top plan view of the phonograph in opened condition; and

FIG. 10 is a front elevational view of the phonograph, in opened condition.

The dominant features of my new design are shown in solid lines in the drawing. The pickup and record stabilizing arms shown in broken lines in FIGS. 7, 8 and 9 have been omitted from FIG. 10 for convenience in illustration.

I claim:

The ornamental design for a portable phonograph or similar article, substantially as shown and described.
